DON N. THOMPSON, OF SYRACUSE, NEW YORK, ASSIGNEE TO PASS & SEYMORE, INC.,
OF SOLVAY, NEW YORK, A CORPORATION OF NEW YORK.

LAMP-SOCKET.

1,313,139.

Specification of Letters Patent. Patented Aug. 12, 1919.

Application filed November 2, 1917. Serial No. 199,854.

To all whom it may concern:

Be it known that I, DON N. THOMPSON, a citizen of the United States, and residing at Syracuse, Onondaga county, State of New York, have invented certain new and useful Improvements in Lamp-Sockets, of which the following is a specification.

This invention relates to quick make and break electrical switches and is particularly suitable for use in connection with lamp sockets, although it is also adapted to be used in wall switches, and in other ways.

The object of the invention is to provide a simple, compact, and inexpensive mechanism which will effect a quick snap action of a movable switch to make or break electrical connection with stationary contacts so that the circuit through a lamp or other current consuming device may be established or broken without arcing.

The invention will be fully disclosed in the following description, taken in connection with the accompanying drawings, in which:

25 Figure 1 is a top plan view of the mechanism secured to the insulating base of a lamp socket, the upper block of the base being removed;

Fig. 2 is a similar view showing the parts 30 in different positions;

Fig. 3 is a vertical section through the base along the actuating spindle and key, the switch member being shown in the "off" position;

Fig. 4 is a side view of the parts which 35 are assembled on the key spindle;

Fig. 5 is a bottom plan view of the lamp socket;

Fig. 6 is a sectional view along the line 40 6-6 of Fig. 1; and

Fig. 7 is an elevation of the switch member.

The insulating base of the lamp socket comprises lower and upper insulating blocks 45 indicated by the numerals 10 and 11 respectively in the drawings, and to the lower block are secured by suitable screws the lamp contacts, comprising the screw shell 12 and center contact 13. Electrically connected to the center contact 13 is the wire terminal 14, the screw shell contact 12 being connected to the wire terminal 15 through the switch mechanism as will hereinafter be fully explained. The current

55 passes, therefore, into the terminal 14 from one of the feed wires and then passes into

the center contact 13, and after going through the lamp or other current consuming device, passes to the screw shell contact 12, thence upwardly through a suitable 60 screw 16, and through the switch mechanism into the other wire terminal 15.

The adjacent faces of the insulating blocks are provided with registering recesses to receive the wire terminals and switch mechanism, as clearly shown in Figs. 1, 2 and 3 of the drawings.

The wire terminal 14 is held within the recess 17 by means of a screw 18 (Fig. 5) passing through the arm 19 of the center 70 contact 13 and upwardly through the lower block 10, the screw in this manner serving to hold both the center contact and terminal 14 in position, and to electrically connect them. The wire terminal 15 is held within 75 a diametrically opposite recess 20 by a screw 21 (Fig. 5) and in an elongated recess 22, midway between the terminal recesses 17 and 20 is located the switch mechanism.

The switch mechanism is also mounted 80 upon the lower block 10 and indeed the upper block 11 serves merely as an insulating cap for the metal parts, and is held to the lower blocks by screws 23 threaded into laterally extending portions 24 and 25 of 85 the wire terminals 14 and 15 respectively.

The arrangement of the insulating blocks, lamp contacts and wire terminals, is old and well known in the art, and is not claimed by the applicant, the novel features of applicant's invention residing in the means for effecting a quick make and quick break of the electrical circuit.

The switch mechanism is mounted on and operated by a spindle 26 journaled at its 95 outer end in the carrying bracket 27 and at its inner end in a recess 28 in the lower block 10. To the outer end of this spindle 26 is secured the key 29 which may be grasped to actuate the switch. Rotatably mounted on 100 the spindle 26 is the switch member 30 comprising an insulating disk 31 having notches 32 cut in the diametrically opposite portions of its periphery, and the switch 33 resting against the disk 31 and having edge portions 105 turned laterally to form flanges to engage the sides of the notches 32 so that the switch member and insulating disk will rotate together.

The switch 33 has integral therewith 110 flanges or arms 34 which are parallel and extend at right angles thereto on opposite

sides of a circular opening 35, through which the spindle 26 extends. As can be seen from Figs. 1 and 2 of the drawings, the switch, which extends across and rests against the face of the insulating disk 31, is raised somewhat above the surface of the insulating disk.

In the rotation of the switch member, the switch and insulating disk engage the stationary contacts 36 and 37, connected to terminal 15 and screw shell 12 respectively, alternately to make and break the circuit, and the disk must necessarily have a limited movement axially of the spindle to compensate for the offset between the insulating disk and switch. In order that the switch member closely engage the stationary contacts, it is loosely mounted on the spindle and a coiled spring 38 is located on the spindle behind the insulating disk which presses the insulating disk and switch against the stationary contacts at all times. This allows axial movement of the switch member against the action of the spring, and insures a firm electrical contact between the switch and stationary contacts.

The forwardly extending arms 34 on the switch member engage with a considerable lost motion the rearwardly extending arms 39 of a cam 40 which is loosely mounted upon the spindle and is connected thereto with a considerable lost motion by a notched member or plate 41 securely fastened to the spindle. Thus the rotating switch member is operably connected to the spindle through the cam 40 with lost motion at two places.

The cam 40 has alternate rounded elevations and depressions 42 and 43 respectively which may be conveniently four each in number, and cooperating with and closely engaging the inclined faces of this cam are the correspondingly inclined faces of the cam 44, also mounted upon the spindle and axially movable thereon, but prevented from rotation by a downwardly extending arm 45 which projects through a slot 46 in the bottom of the carrying bracket 27. A strong coiled spring 47 located between the vertical flange of the carrying bracket 27 and the cam 44, and bearing against these portions, tends to keep the inclined faces of the two cams constantly together in the position shown in Fig. 1, since under the action of the spring the elevations of one cam will seek the depressions of the other. When the spindle is rotated, however, the notched member 41 engages the arms 39 of the cam 40 and the arms 39 engage the arms 34 of the switch member to rotate the latter to make or break the circuit.

The function of the cooperating cams, aided by the spring 47, is to effect a snap action of the switch member, and this result is very effectually produced thereby, as will now be fully explained. Assuming the key

to be in the position shown in Fig. 1, and it is desired to break the current connection, the spindle is rotated in either direction, as desired. Assuming it to be rotated in a clock-wise direction, the spindle will turn some distance before the notched member 41 engages the arms 39 to rotate the cam 40 and the cam 40 will rotate a further distance before the arms 39 engage the arms 34 to rotate the switch member. As the cam 40 rotates, however, its inclined surfaces press against the correspondingly inclined surfaces of the cam 44 and ride over them to wedge or push the last mentioned cam forwardly on the spindle and away from the cam 40. This forward motion of cam 44 continues until it has reached the position indicated in Fig. 2, when the elevations of the two cams are bearing against each other and the spring 47 is compressed. A slight further clock-wise rotation of the spindle will cause the elevations of cam 40 to pass over the rounded elevations of cam 44 and thereupon the spring 47 which has been put under considerable compression, expands and drives the cam 44 toward the cam 40 and the elevations of cam 44 ride down the inclines of cam 40 until they rest in the depressions therein.

This causes a very quick rotation of cam 40 and the rotating switch member is instantly thrown from its on position to its off position, the lost motion permitting the switch member to rotate due to its inertia, even after the cam 40 has ceased to rotate. This insures a very quick break of the electrical connection between the contacts 17 and 18.

Having broken the connection, it may be reestablished by turning the key in either direction, the parts performing identically the same functions as before, though in the reverse direction, if the spindle is rotated in a counter clock-wise direction.

From the above description, it is apparent that the invention provides a simple and inexpensive switch, but one which makes and breaks the contact at high speed, which is necessary to prevent arcing. The invention may be used not only with lamp sockets such as shown in the drawings, but with wall switches and other electrical switches. A suitable inclosing shell is, of course, provided to properly insulate the various parts of the mechanism, but as this is no part of my present invention, I have omitted to show and describe the same for the sake of brevity and clearness, such protecting shells being old and well known in the art.

Having thus described the invention what is claimed as new and desired to be secured by Letters Patent is:—

1. In a quick make and break switch, the combination with an insulating base, of a stationary contact mounted thereon, a rotatable spindle mounted on said base, a rotary

- switch rotatably mounted on said spindle and adapted to make and break electrical connection with said stationary contact, a rotary cam having lost motion connections 5 with said spindle and said rotary switch, a non-rotatable cam movable axially of said spindle, and a spring holding said cams in mutual engagement, said spring causing the axially movable and non-rotatable cam to 10 rotate said rotatable cam and switch member with a snap action to make or break the connection with the stationary contact when the switch has been partially rotated by said spindle and rotary cam.
- 15 2. In a quick make and break switch, the combination with an insulating base of two opposed stationary contacts mounted thereon, a rotatable spindle mounted on said base, a rotary switch rotatably mounted on 20 said spindle and adapted to make and break electrical connections between said stationary contacts, a rotary cam having lost motion connections with said spindle and said rotary switch, a non-rotatable cam 25 movable axially of said spindle, a spring holding said cams in mutual engagement, said spring causing the axially movable and non-rotatable cam to rotate said rotatable cam and switch member with a snap action 30 to make or break the electrical connection between the stationary contacts when the switch has been partially rotated by said spindle, and rotary cam.
3. In a quick make and break switch, the 35 combination with an insulating base, of a stationary contact mounted thereon, a rotatable spindle mounted on said base, a rotary switch member having alternate conducting and non-conducting portions, a 40 spring pressing said switch member against said contact at all times, a rotary cam having lost motion connections with said spindle and said rotary switch, a non-rotatable cam movable axially of said spindle, and a 45 spring holding said cams in mutual engagement, said spring causing the axially movable and non-rotatable cam to rotate said rotatable cam and switch member with a snap action to make or break the connection 50 with the stationary contact when the switch has been partially rotated by said spindle and rotary cam.
4. In a quick make and break switch, the 55 combination with an insulating base, of a stationary contact mounted thereon, a rotatable spindle mounted on said base, a rotary switch member having alternate conducting and non-conducting portions, arms 60 projecting laterally from said switch member, a rotary cam connected with lost motion
- to said spindle and having laterally projecting arms adapted to engage with lost motion the arms projecting from said rotary switch member, a non-rotatable cam movable axially of said spindle, and a spring holding said cams in mutual engagement, said spring causing the axially movable and non-rotatable cam to rotate said rotatable cam and switch member with a snap action to make or break the connection with the stationary contacts when the switch has been partially rotated by said spindle and rotary cam.
5. In a quick make and break switch, the combination with an insulating base, of a stationary contact mounted thereon, a rotatable spindle mounted on said base, a rotary switch rotatably mounted on said spindle and adapted to make and break electrical connection with said stationary contact, a rotary cam having alternate rounded elevations and depressions, and having lost motion connections with said spindle and said rotary switch, a non-rotatable cam movable axially of said spindle and having alternate rounded elevations and depressions corresponding to the elevations and depressions of the rotary cam and adapted to engage the same, a spring holding said cams in mutual engagement, said spring causing the axially movable and non-rotatable cam to rotate said rotatable cam and switch member with a snap action to make or break the connection with the stationary contact when the switch has been partially rotated by said spindle and rotary cam.
6. In a quick make and break switch, the combination with an insulating base, of a stationary contact mounted thereon, a rotatable spindle mounted on said base, a rotary switch rotatably mounted on said spindle and adapted to make and break electrical connection with said stationary contact, a rotary cam connected with lost motion to said switch member, a notched member mounted on said spindle and engaging with lost motion said rotary cam, a non-rotatable cam movable axially of said spindle, and a spring holding said cams in mutual engagement, said spring causing the axially movable and non-rotatable cam to rotate said rotatable cam and switch member with a snap action to make or break the connection with the stationary contact when the switch has been partially rotated by said spindle and rotary cam.

In testimony whereof I affix my signature.

DON N. THOMPSON.
